DESIGN FOR A LUMINAIRE

Joshua Gordon Lippincott, Scarsdale, N. Y., assignor to Holophane Company, Inc., New York, N. Y., a corporation of Delaware

Application August 12, 1944, Serial No. 114,852

Term of patent 7 years

(Cl. D48—16)

To all whom it may concern:

Be it known that I, Joshua Gordon Lippincott, a citizen of the United States of America, and a resident of Scarsdale, in the county of Westchester and State of New York, have invented a new, original, and ornamental Design for a Luminaire, of which the following is a specification, reference being had to the accompanying drawing, forming a part thereof.

In the drawing:

The figure is a side elevational view of a luminaire showing my new design.

The luminaire is circular throughout its height.

I claim:

The ornamental design for a luminaire, as shown and described.

JOSHUA GORDON LIPPINCOTT.
